(57) **CLAIM**

The ornamental design for a tool bit, as shown and described.

DESCRIPTION

FIG. 1 is a perspective view of a tool bit showing my new design;

FIG. 2 is a front elevational view of FIG. 1;

FIG. 3 is a rear elevational view of FIG. 1;

FIG. 4 is a left side view of FIG. 1;

FIG. 5 is a right side view of FIG. 1;

FIG. 6 is a top plan view of FIG. 1; and,

FIG. 7 is a bottom plan view of FIG. 1.

The broken lines in the figures are for illustrative purposes only and depict portions of the design that form no part of the claim.

1 Claim, 4 Drawing Sheets

FIG. 1

FIG. 2

FIG. 3
